Primary Examiner — Susan Moon Lee*(74) Attorney, Agent, or Firm* — Wells St. John P.S.(57) **CLAIM**

We claim the ornamental design for a door sill, as shown and described.

DESCRIPTION

FIG. 1 is a front perspective view of a door sill;
 FIG. 2 is a top plan view thereof;
 FIG. 3 is a bottom plan view thereof;
 FIG. 4 is a front view thereof;
 FIG. 5 is a rear view thereof; and,
 FIG. 6 is a side view thereof, the opposite side view having the same configuration.

The door sill of the present design is depicted in a 'broken-away' manner. The appearance of any portion of the article between the break lines forms no part of the claimed design.
